Primary Examiner — Kelley Donnelly(74) *Attorney, Agent, or Firm* — Platinum Patents; Jordan Kuhn(57) **CLAIM**

The ornamental design for a beverage tray with illuminating pattern, as shown and described.

DESCRIPTION

FIG. 1 is a perspective view of the beverage tray with illuminating pattern showing our new design, wherein the illuminating pattern region is in an illuminating state;

FIG. 2 is a top view of the beverage tray with illuminating pattern thereof; and,

FIG. 3 is a front view of the beverage tray with illuminating pattern thereof;

FIG. 4 is a perspective view of the beverage tray with illuminating pattern showing our new design, wherein the illuminating pattern region is in a non illuminating state;

FIG. 5 is a top view of the beverage tray with illuminating pattern thereof; and,

FIG. 6 is a front view of the tray with illuminating pattern thereof.

All broken lines are directed to environment and are for illustrative purposes only. The broken lines form no part of the claimed design. The broken radiating lines in FIGS. 1-3 indicate illumination. The dark shading in FIGS. 4-6 compared to the same region shown unshaded in FIGS. 1-3 indicates a contrast in appearance between unlit and lit regions, and does not depict any particular color, texture, or material.
